JORDAN ENGINE WITH CRIMPED MEMBERS

Archer Le Roy Bolton, North Andover, Mass., assignor to John W. Bolton & Sons, Inc., Lawrence, Mass., a corporation of Massachusetts

Application April 18, 1935, Serial No. 17,056

6 Claims. (Cl. 92—27)

This invention relates to Jordan engines such as are used in refining paper stock in the manufacture of paper. Such Jordan engines include an outer truncated conical shell member from 5 which cutting or stroking members project inwardly, and a plug member which has members which project outwardly therefrom, the plug revolving inside the shell and the projecting members coming very close to being in contact with 10 each other.

The inwardly projecting members from the shell are known as knives, and are generally arranged in two or more sets longitudinally, the knives of each set being bent at the middle, while 15 the projecting members of the plug are generally known as bars and usually extend in a substantially straight line from the large to the small end, or part way from the large to the small end.

The stock is usually introduced at the small 20 end and travels to the large end at the same time that it is carried around by the plug at a high rate of speed. As the stock treating members or bars of the plug and the knives of the shell have their faces very close together, there is a brushing and 25 separating, and to some extent a cutting action, which takes place as the stock travels through the engine.

The speed is very great and the power in some 30 cases very great, so that it has often been found necessary to make the projecting members quite thick and of very strong material. I have discovered that by crimping the operating edge of all or some of the knives, whether bent or straight, or of the bars in the plug, particularly if the 35 crimped edges are operating against straight edges, a cutting action takes place and as a crimped edge is much stronger than a straight edge of the same thickness, I can reduce the thickness of these members without injuring their 40 strength.

What I will call the bottom part is that part which ordinarily is held between tapering separators of wood or other material, and what I will call the top part is the part lengthwise which 5 projects from some of these separators, the top edge being the free edge and being the part which I crimp.

As the top part of the knives or bars with the 50 top of the separators form longitudinal channels, the crimping also acts to some extent as a baffle and changes the direction of the current of stock flowing through the channel.

I am aware that the edges of beater bars 55 which are carried on the surface of the cylindrical beater rolls of beater engines have been corrugated,

gated, but I believe I am the first to use crimped cutting edges in a Jordan shell or a Jordan plug.

In a beater, the stock travels and flows at a right angle to the bars, while in a Jordan, it travels spirally over the knives but flows between them. 5

In the drawing, Fig. 1 is an isometric view of part of the end of a Jordan shell showing parts of three conical sections of filling, each provided with angular knives with crimped edges and part 10 of a Jordan plug.

Fig. 2 is a view similar to Fig. 1 showing straight knives, some of which are crimped and some of which are not crimped.

Fig. 3 is an isometric view of the small end of 15 a Jordan plug with straight crimped bars.

Fig. 4 is an elevation showing part of a crimped member for a Jordan engine, shown as part of a bent knife but it also serves for a straight knife or a straight bar. 20

Fig. 5 is a plan view of Fig. 4.

Fig. 6 is a vertical section on line 6—6 of Fig. 5.

Fig. 7 is a view similar to Fig. 6 of a member with a sharpened edge.

Fig. 8 is an isometric view of a modified form 25 of stock treating member having a crimped edge.

In the drawing, S represents the permanent or fixed shell of a Jordan engine, and in Fig. 1, A represents the lining as a whole, while in Fig. 2, B represents the lining as a whole. P represents 30 the plug which cooperates with shell S and Q represents the cutting or working surface of the plug.

In Fig. 1, the lining A is made up of a plurality of angularly bent knives K, between which are 35 shown the usual angularly bent separators 90 of wood or other suitable material. These separators taper lengthwise from the large end to the small, and are shown as of the usual keystone cross section. Other parts of this lining may be 40 an anchor bar or bars, cheek pieces and a wedge or wedges, all of which are well-known and commonly used in the trade.

Each knife, such as K, is formed or made of a strip of metal with substantially parallel lengthwise edges and ends, being substantially of rectangular shape, and originally being flat and straight and of the same thickness throughout. 45

1 represents the bottom edge, and 2 the bottom part longitudinally, while 3 represents the top 50 part and 4 the top edge. The bottom part 2 extends to a height which is the same as, or slightly higher, than the height or thickness of the adjoining separators, and the top part 3 is crimped or corrugated, which means formed with con- 55

volutions of successive curves or half circles, first in one direction, and then in the other direction. In the process of forming this crimped top part 3, the top edge 4 becomes substantially longer than 5 the bottom edge 1, or bottom part 2, so that a longer cutting or work-operating edge is produced without increasing the size of the shell or without adding an increased number of knives. The crimping makes the top part and top edge 10 considerably thinner than the bottom part. Each knife K, as shown, is also bent at 9 in the usual manner and its top edge 5 may be sharpened as shown in Fig. 7. This sharpening, preferably, is accomplished while the strip from which it is 15 made, is straight and flat, before crimping.

As shown at H in Fig. 2, the knives can be straight and the bend 9 omitted so that 11 represents the bottom edge, 12 the bottom part, 13 the top part, and 14 the top edge.

20 In the same way, straight bars such as C, forming with the tapering separators 20, the operating part Q of the plug P would ordinarily be without any bend such as 9. In these bars C, 21 represents bottom edge, 22 the bottom part, 23 25 the top part, and 24 the top edge.

Fig. 4 is a side elevation of part of a crimped knife or bar, and Fig. 5 is a plan view of the same, while Fig. 6 is an exaggerated cross section to show the thinness of the crimped part 30 as compared to the original thickness. Fig. 7 is like Fig. 6 but with the cutting edge sharpened.

Instead of using a metal strip of the same original thickness throughout, in some cases, I may use a member such as E, in which the bottom part 30, from shoulder 32 down to the bottom edge 31, is very much thicker than the top part 33 and the crimped top edge 34 sharpened at 35.

As shown in Fig. 2, some of the cutting or 40 stock treating members can be crimped as shown at H, while others may be uncrimped and straight as shown at L.

The co-action of a crimped member in the shell with an uncrimped member on the plug, or vice versa, produces a very desirable cutting action 45 although crimped member against crimped member works very well, as also shown in Fig. 2.

I prefer to use for my stock treating members, strips of high alloy steel of approximately 50 over 200,000 pounds tensile strength per square inch in place of the usual carbon steel of approximately 60,000 pounds per square inch, and I prefer to make the ratio of the thickness of my metal strips to their height more than 1 to 10. A preferred construction is $\frac{1}{8}$ inch thick and two 55 inches in height, the crimping extending down about $\frac{3}{4}$ of an inch and being approximately $\frac{1}{8}$ of an inch at the cutting edge crossways from the outside of one curve to the outside of the other. With a 15 inch strip, this crimping spreads the cutting edge to 18 or 20 inches.

The crimping, therefore, reduces the thickness of the top part from $\frac{1}{32}$ to $\frac{1}{16}$, and the top edge can conveniently be sharpened so that it is about $\frac{1}{32}$ of an inch in thickness.

60 It is obvious that the Jordan shell lining, such as shown in Figs. 1 and 2, or the Jordan plug

jacket, such as shown in Fig. 3, might be of the old type of lining or jacket made up of a large number of independent knives, bars, and separators, or of the preassembled type, either split or unsplit, which are assembled and held together at the machine shop and shipped as a unit to the paper mill.

I claim:

1. The combination in a Jordan engine which includes a truncated conical shell and a truncated conical plug; of tapering separators; and cutting members between some of the separators, each made of a strip of metal which is flat along its bottom part and which projects from the adjoining separators and is crimped along its 10 top part and top edge.

2. The combination in a Jordan engine which includes two members which are a truncated conical shell and a truncated conical plug; of tapering separators in each; cutting members between 20 some of the separators carried by one member, each made of a strip of metal which is flat along its bottom part and which projects from the adjoining separators and is crimped along its top part and top edge, which edge is proximate 25 to the uncrimped edge of a cutting member carried by the other Jordan engine member; and such other cutting member and such other Jordan member.

3. The combination with a truncated conical 30 Jordan engine shell; of angularly bent, tapering separators of keystone cross section; and cutting members which are angularly bent laterally between some of the separators, each cutting member being made of a strip of metal which is 35 flat along its bottom part and which projects from the adjoining separators and is crimped along its top part and top edge.

4. The combination with a truncated conical member of a Jordan engine; of tapering separators of keystone cross section; and cutting members between some of the separators, each made of a strip of metal which is flat along its bottom part where it comes in contact with separators and which projects from such separators 45 and is crimped along its top part and top edge.

5. The combination in a preconstructed truncated conical Jordan engine shell lining unit; of angularly bent, tapering separators of keystone cross section; and cutting members which are 50 angularly bent laterally between some of the separators, each cutting member being made of a strip of metal which is flat along its bottom part and which projects from the adjoining separators and is crimped along its top part and top edge.

6. A preconstructed bodily transportable truncated conical member for a Jordan engine made up of tapering separators of keystone cross section; and cutting members between some of the separators, each made of a strip of metal which is flat along its bottom part where it comes in contact with separators and which projects from such separators and is crimped along its top part and top edge.

65 ARCHER LE ROY BOLTON.
